UNITED STATES PATENT OFFICE.

ROBERT L. HORSLEY, OF FORT WORTH, TEXAS.

BALE-TIE BUCKLE.

1,124,227.

Specification of Letters Patent.

Patented Jan. 5, 1915.

Application filed April 16, 1914. Serial No. 832,218.

To all whom it may concern:

Be it known that I, ROBERT L. HORSLEY, a citizen of the United States, residing at Fort Worth, in the county of Tarrant and State of Texas, have invented certain new and useful Improvements in Bale-Tie Buckles, of which the following is a specification.

My invention relates to fastening devices for the bands or ties of compressed bales of cotton or other material, and more particularly to wire buckles or binders for connecting the ends of bands or ties on the bales after the bales have been compressed, and the object is to provide fastening devices which can be economically manufactured and which will be capable of resisting enormous pressure and which can be quickly and easily placed on the bands or ties. In baling cotton it is necessary to put the buckles or fastening devices on with great rapidity, particularly at the compresses.

Other objects and advantages will be fully explained in the following description and the invention will be more particularly pointed out in the claims.

Reference is had to the accompanying drawings which form a part of this application.

Figure 1 is a front or exterior view of the two ends of a bale tie secured by one of the improved buckles or fastening devices. Fig. 2 is an edge view of the same. Fig. 3 is a front view of a buckle on a larger scale than Fig. 1. Fig. 4 is a front view of a buckle spread for inserting the ends of the ties.

Similar characters of reference are used to indicate the same parts throughout the several views.

The improved buckle is made preferably of a single piece of steel wire. One of the objects and advantages of the buckle is that cotton bale ties can be placed on the bales with the free ends of the tie folded under the tie so that there will be no projecting ends. In use the projecting ends on cotton bales are called "spiders" and there is a law against such projecting ends. With my improved buckle there can be no projecting ends if put on the bales as intended and adapted to be put in use.

The buckle 1 is secured to the end 2 by simply running the end of the tie through the buckle and folding the end 3 back between the tie and the bale. This may be done at the bench where the tie can be han-

mered down on the buckle. The other part of the tie 4 is secured on the buckle 1 by first folding the end 5 and then shifting the loop, formed by folding in between the doubled portions 6 and 7 and at the same time rotating the buckle until the loop passes the end 8 of the portion 7. The loop can then engage both double portions 6 and 7, as shown in Fig. 2, and then the loop is shifted to the position shown in Fig. 1. Bights or short hooks 10 and 9 are formed at the ends of the wire which form the buckle and these bights prevent the wire from being drawn out straight when pressure comes on the tie. One end of the buckle or wire will brace the other against the loop of the tie. When pressure comes on the band or tie, the outer edges 12 of the tie will be stretched and drawn so that the tie will conform to the contour of the engaged part of the buckle. When the tie is thus stretched and made to conform to the bar or part of the tie engaged, there can be no slipping of the tie on the bar 13. The same stretching takes place at the outer edges 14 of the tie. This stretching makes crimps in the loop portion of the tie. The buckle is substantially quadrangular with tie engaging members 6 and 7 at one side, 13 at the other side with side bars 1 and 15.

Instead of placing the buckle on the ends of the tie as above described, the buckle is spread as shown in Fig. 4. The upper end 2 of the tie is secured to the member 13, as above described and then the other end 4 of the tie is shifted between the ends of the bars 6 and 7 and brought to the position of the dotted outline. The loop is then pressed against the end 8 with the hand of the operator pressing on the bar 15. The bars 1 and 15 are pressed to the position shown in Fig. 3 and the loop of the tie can be dropped to the position shown in Figs. 1 and 2. The bars 1 and 15 will tend to spread and thus clamp the loop in the bights 9 and 10.

What I claim, is,

1. A bale tie buckle comprising a single piece of steel wire bent to form two tie engaging members and two side bars, and to form hooks at the ends of the wire, one of said tie engaging members being formed by lapping the ends of the wire past each other after the tie is inserted, and said hooks being projected inwardly so as to hook over the edges of the tie to prevent the ends of

the wire from being drawn out when strain comes upon the tie.

2. A bale tie buckle comprising a single piece of steel wire having hooks or bights formed at the ends thereof and bent to form two tie engaging members and two side bars, one of said tie engaging members being formed by lapping portions of said wire and said side bars holding the portions of 10 said wire (to be lapped) normally spread laterally until the tie is inserted in said buckle and said hooks or bights being projected inwardly so as to hook over the edges of the tie to prevent spreading of the buckle.
- 15 3. A bale tie buckle comprising a single piece of steel wire bent to form two tie engaging members and two side bars, one of said tie engaging members being curved at the juncture with said side bars for forming crimps in the edges of the tie to prevent slipping of the tie on the buckle and the 20 other tie engaging member being formed

by lapping portions of said wire after the tie is inserted.

4. A bale tie buckle comprising a single 25 piece of wire bent to form a tie-engaging member and two side bars and to form lapping members on said side bars, said side bars holding said lapping members laterally spread until the tie is inserted, said lapping 30 members to be lapped after the tie is inserted to form a second tie-engaging member and said lapping members having their terminals bent inwardly over the edges of the tie to prevent disengagement of the 35 buckle.

In testimony whereof, I set my hand in the presence of two witnesses, this 8th day of April, 1914.

ROBERT L. HORSLEY.
